UNITED STATES PATENT OFFICE.

JOHN CONNOR, OF JERSEY CITY, NEW JERSEY.

IMPROVEMENT IN LIFTING-HOOKS FOR STRIKING-CLOCKS.

Specification forming part of Letters Patent No. **155,224**, dated September 22, 1874; application filed August 5, 1874.

To all whom it may concern:

Be it known that I, JOHN CONNOR, of Jersey city, in the county of Hudson and State of New Jersey, have invented a new and Improved Lifting-Hook for Striking-Clocks, of which the following is a specification:

Figure 1 is a face view, partly in section, of a striking-clock provided with my improved lifting-hook. Figs. 2 and 3 are detail perspective views, showing the lifting-hook in different positions.

Similar letters of reference indicate corresponding parts in all the figures.

The object of this invention is to provide American striking-clocks of all kinds with mechanism that will allow the hands to be turned back without interfering with the striking mechanism, and without injury to any of the parts of the clock.

The invention seeks to attain this end without adding anything to the mechanism of ordinary clocks; and differs, in this regard, from the devices heretofore proposed, which, in order to attain the same end, require the interposition of additional levers, or other mechanism.

The invention consists, solely, in a new form of lifting-hook, whereby the same is enabled to pass the wire of the lock-work without affecting the striking mechanism whenever the hands are set backward; while, when the hands are set forward, it will lift the wire of the lock-work, and cause the clock to strike.

In the drawing, the letter A represents the frame of a suitable American or "yankee" clock. B is the spindle carrying the minute-hand, and rotated, by connection with the mainspring, in the usual manner. This spindle carries, as usually, a projecting lifting-hook, C, for actuating the lock-work—that is, the striking mechanism—once every hour, or at other suitable intervals. b is that wire of the lock-work which extends toward the spindle B, and is to be directly actuated by the lifting-hook.

The end of the wire b rests against the body of the spindle, as indicated, and when the spindle B is turned to the right, in the direction of the arrow shown in Fig. 3, the

lifting-hook will enter beneath the wire b, and lift said wire from contact with the spindle B, and thus affect the striking mechanism in the requisite manner.

The peculiarity of my lifting-hook is, that its front edge a—that is to say, the edge which is turned toward the wire b—is inclined toward the spindle B. The angle of inclination may be about thirty-five degrees, more or less, where heretofore the same edge of the lifting-hook was always ninety degrees to the axis of the spindle. The same edge a, besides being inclined to the spindle, is also beveled with reference to the faces of the lifting-hook, causing the left-hand face of the hook to be narrower than the right-hand face when the hook projects upward from the spindle. Thus the edge a is doubly inclined.

The effect of this shape is that, if the hook is turned in the direction of the arrow 1, (shown in Fig. 2)—that is to say, if the minute-hand is set back—the lifting-hook, on reaching the wire b, will not lift said wire off the spindle, nor will it bend or break the wire, or be bent or broken itself, but it will, with its doubly-inclined edge a, come in contact with the end of the wire b, and slightly push the said wire, in line with the axis of the spindle, in the direction indicated by the arrow 2 in Fig. 2. This very slight motion is permitted to the wire b by its spring, and, after the hook C has passed it, the wire b will resume its former position by virtue of the same springing property. When, however, the spindle B is turned to the right, as already stated, the outer edge or end of the hook C will come under the wire b, and lift it off the spindle, and cause the clock to strike.

The lifting-hook may be made of a plate of brass, of nearly triangular form, as shown in the drawing; or it may be made of a single wire, set inclined on the spindle B, the effect being, in both cases, identical; but it is preferable to use the hook in the form shown, because it thereby acquires a broader end, and is more likely to take hold of the wire b, causing the clock to strike even if the parts of the clock should not be made with the utmost care and exactitude.

One additional advantage of my improved lifting-hook is, that the striking-wire which is appended to many clocks for causing them to strike whenever desired, can be dispensed with, because I can make a clock having my improved lifting-hook strike as often as desired by merely drawing the minute-hand backward and forward over the figure 12 of the dial.

I claim as my invention—

In a striking-clock, the lifting-hook C, having the inclined edge *a*, for operation substantially as herein shown and described.

JOHN CONNOR.
